DESIGN FOR A CASING FOR FLUID FILTERS

Arthur David Becker, Painesville, Ohio

Application January 28, 1937, Serial No. 67,322

Term of patent 3½ years

To all whom it may concern:

Be it known that I, Arthur David Becker, a citizen of the United States, residing at Painesville, in the county of Lake and State of Ohio, have invented a new, original, and ornamental Design for a Casing for Fluid Filters, of which the following is a specification, reference being had to the accompanying drawing, forming part thereof.

Figure 1 is a view in side elevation of a casing for fluid filters, showing my new design.

Figure 2 is a top plan view thereof.

Figure 3 is an end elevational view.

I claim:

The ornamental design for a casing for fluid filters, as shown.

ARTHUR DAVID BECKER.
